(57) **CLAIM**

The ornamental design for a handle for a kitchen and eating utensil, as shown and described.

DESCRIPTION

FIG. 1 is a front view of a handle for a kitchen utensil and eating utensil showing our new design.

FIG. 2 is a side view thereof, the opposite side view being a mirror image;

FIG. 3 is a rear view thereof;

FIG. 4 is a top view thereof shown in an alternate environment;

FIG. 5 is a front perspective view thereof shown in the alternate environment of FIG. 4; and,

FIG. 6 is a front view thereof in an alternate condition.

The broken line showing of a tool head is for the purpose of illustrating portions of the article and forms no part of the claimed design.
